(57) **CLAIM**

The ornamental design for a controller for wireless radios, as shown and described.

DESCRIPTION

FIG. 1 is a perspective view of the controller for wireless radios;

FIG. 2 is a front view of the controller for wireless radios;

FIG. 3 is a rear view of the controller for wireless radios;

FIG. 4 is a left side view of the controller for wireless radios;

FIG. 5 is a right side view of the controller for wireless radios;

FIG. 6 is a top view of the controller for wireless radios; and,

FIG. 7 is a bottom view of the controller for wireless radios. The portion shown by broken lines is for illustrative purposes only and forms no part of the claimed design.
